UNITED STATES PATENT OFFICE.

GEORGE P. TILTON, OF NEWBURYPORT, MASSACHUSETTS, ASSIGNOR TO
THE TOWLE MANUFACTURING COMPANY, OF SAME PLACE.

DESIGN FOR A SPOON, &c.

SPECIFICATION forming part of Design No. 19,205, dated July 9, 1889.

Application filed June 5, 1889. Serial No. 313,203. Term of patent 7 years.

To all whom it may concern:

Be it known that I, GEORGE P. TILTON, of Newburyport, in the county of Essex and State of Massachusetts, have invented and produced 5 a new and original Design for Spoons, Forks, and other Articles of Flat Ware, of which the following is a full, clear, and exact description.

The feature of my design consists in the 10 novel configuration and ornamentation of the face or front portion of the handle of a spoon, fork, or other article of flat ware, as shown in the accompanying drawing, forming a part of this specification, and which represents the 15 design as applied to the face portion of the handle of a spoon.

A indicates the handle, having its outer end 20 of a rounded approximately semicircular facial configuration, terminating in straight lines. Upon this outer end portion of the 25 handle, and bounded by the rounded marginal configuration of said end portion, so as to lie wholly within the upper end portion of the handle and extending out to its rounded marginal outline, is an ornament which includes a series of figures in relief, the whole 30 of which forms a single ornamentation. These figures consist of two scroll-like figures *a a*, ornamented on their convex margins by bead-like figures *b b*, with a ribbed figure *c* between the scrolls, and which appears to connect the 35 scrolls, and which also appears to cross or overlie the stems of two reverse fan-like clusters *d e* of

curved tapering stem-like figures, which serve to complete the ornament, the one or lower cluster *d* resembling a series of clavate-like figures having mainly curved stems, and the other or outer end cluster *e* conforming on its outer edge to the general outline of the upper rounded end portion of the handle, with which it coincides.

I claim—

The design for spoons, forks, and other articles of flat ware herein shown and described, the same consisting of the handle having a 45 rounded approximately semicircular outer end configuration, terminating in straight lines, and having an ornamentation in relief within said rounded end portion and bounded by it, comprising the scroll-like figures *a a*, 50 having bead-like ornaments *b b* on the outside of their convex margins, the ribbed figure *c* between the scrolls, and the reverse clusters *d e* of curved tapering stem-like figures with their stems appearing to underlie the ribbed 55 figure *c*, and the upper one *e* of said clusters conforming in its general outline to the outline of the upper rounded end portion of the handle, while the lower one *d* of said clusters resembles a series of clavate-like figures having mainly curved stems, as set forth.

GEORGE P. TILTON.
